UNITED STATES PATENT OFFICE.

EDWARD A. HALBLEIB, OF ROCHESTER, NEW YORK, ASSIGNOR TO NORTH EAST ELECTRIC COMPANY, OF ROCHESTER, NEW YORK, A CORPORATION OF NEW YORK.

ENGINE-STARTING APPARATUS.

1,072,002.

Specification of Letters Patent.

Patented Sept. 2, 1913.

Application filed November 6, 1911. Serial No. 658,902.

To all whom it may concern:

Be it known that I, EDWARD A. HALBLEIB, a citizen of the United States, and resident of Rochester, in the county of Monroe and State of New York, have invented certain new and useful Improvements in Engine-Starting Apparatus, of which the following is a specification.

This invention relates to apparatus for automatically starting an internal-combustion engine, and it is particularly useful in connection with engines employed upon motor-vehicles, although applicable, in certain of its features, to engines used in other connections.

One object of the invention is to produce apparatus of the kind in question so arranged and connected with the engine that it may be conveniently mounted upon a motor-vehicle in a position where it will not occupy valuable space within the interior of the vehicle or adjacent the engine. To this end I have devised an arrangement in which the apparatus, or the greater part thereof, is mounted upon, or carried by, a frame adapted to be placed transversely in front of the engine, and to be supported upon the side frame-members of the vehicle, the mechanism upon this frame being connected with the forward end of the crank-shaft of the engine by any suitable form of connection. In conjunction with this feature of the invention I preferably employ a particular arrangement of the parts of the mechanism which conduces to compactness and efficient operation, and which constitutes a feature of the invention hereinafter claimed.

Other objects of the invention, and the features of construction by which they are attained, will be set forth hereinafter in connection with the description of the illustrated embodiment of the invention.

In the accompanying drawings:—Figure 1 is a front-elevation of engine-starting apparatus embodying the present invention, together with a portion of the front of a motor-vehicle upon which the apparatus is mounted; Fig. 2 is a diagram of the complete apparatus, showing the parts in operative position; Fig. 3 is a vertical section through a part of the apparatus, including the gearing, the air-pump and the controlling-mechanism; Fig. 4 is a section on the line 4—4 in Fig. 3; Fig. 5 is an end-view of

the apparatus, looking from left to right in Fig. 3; Fig. 6 is a section on the line 6—6 in Fig. 3; Fig. 7 is a section on the line 7—7 in Fig. 3; Fig. 8 is a partial section on the line 8—8 in Fig. 3; and Fig. 9 is a partial plan-view, in section on the line 9—9 in Fig. 8.

The invention is illustrated as embodied in apparatus of the general type set forth in my previous application filed October 9, 1911, Serial No. 653,671, and accordingly some of the novel features of the apparatus are not herein claimed.

Referring first to Figs. 1 and 2, the illustrated embodiment of the invention is a self-contained apparatus in which nearly all of the working parts are mounted upon a frame or base-plate which is carried by transverse supports 12, and these supports are fixed, at their ends, to the side frame-members 13 of the motor-vehicle, thus supporting the weight of the apparatus entirely upon these frame-members. The apparatus is inclosed within a removable casing 11, and is supported at such a height that its mechanism may be connected, through the rear of the casing, with the forward end of the crank-shaft of the engine of the vehicle, in a manner which will be presently described. By this arrangement the apparatus is conveniently and accessibly mounted in a position in which it does not obstruct the necessarily restricted space within the body of the vehicle and adjacent the engine and the accessory parts, and the apparatus may be readily applied to vehicles of various designs without substantial modification either in the apparatus or in the vehicles.

The principal operative elements of the apparatus are shown in Fig. 2, where they are represented diagrammatically. An internal-combustion engine of ordinary form is illustrated, having four cylinders 14 provided with pistons 15 which are connected, in the usual manner, with the crank-shaft 18 of the engine. Each cylinder is shown as provided with an inlet-valve 16 and an exhaust-valve 17.

The selector for introducing the motive-fluid automatically into the engine-cylinders, in succession, at the proper time is illustrated as comprising a casing 19 provided with four outlet-ports 20 which are connected, respectively, through pipes 21,

with the four cylinders. Within the casing 19 is a rotary valve-member 22 supplied, at its center, with motive-fluid through a pipe 23. The rotary member 22 has a port 24 adapted to communicate with the outlet-ports 20 singly and successively as the member 22 rotates.

I have not illustrated the selector in detail, nor shown the means for actuating it, 10 as such devices are known in the art, and it will be understood that the rotary member may be actuated, in the usual manner, by connection with a rotating part of the engine, such, for example, as the cam-shaft, or half-time shaft, the arrangement being 15 such that the port 24 registers with each of the ports 20 as the piston in the corresponding cylinder reaches a position in which it is about to begin the down-stroke which, in 20 its normal cycle of operations, constitutes the expansion-stroke in that cylinder. This is shown in the diagram, where the selector is in position to introduce motive-fluid into the right-hand cylinder, in which the piston is midway in its downward expansion-stroke, both the inlet-valve and the exhaust-valve 25 being closed. The piston in the second cylinder is in the performance of its compression-stroke, while the third and fourth pistons are in the performance of their suction-stroke and exhaust-stroke, respectively, as 30 indicated by the positions of the valves in the corresponding cylinders.

The selector is provided with a passage 35 25 which constitutes an outlet-port and bypass to relieve compression in the cylinder in which the piston is in the performance of the compression-stroke. As shown in Fig. 2, the passage 25 is in such position that, 40 while the motive-fluid is admitted to the first or right-hand cylinder, free communication is afforded between the second and third cylinders, thus permitting air to escape from the second cylinder and enter the third cylinder. In this manner the apparatus is relieved from the resistance which 45 would be opposed to its action by compression in the second cylinder, thus facilitating and rendering more certain the starting operation. To prevent the flow of gas from 50 the engine-cylinders through the pipes 21 and the selector during the normal operation of the engine, shut-off valves 67 are provided in these pipes, and these valves 55 may all be actuated by a single manually-operable member 68 located in convenient position on the vehicle.

The flow of motive-fluid through the pipe 23 is controlled by a valve 26, which is more 60 particularly described hereinafter. Fig. 2 also illustrates a reservoir 27, of substantial capacity, introduced in the pipe 23, which serves to accumulate a certain amount of motive-fluid under pressure, thus providing 65 for the charging of each cylinder more rap-

idly than could be accomplished by the direct action of a pump. This arrangement is disclosed in my said application. This reservoir is particularly useful where the apparatus is employed to start the engine by 70 the action of inert motive-fluid, such as pure compressed air or other gas, operating upon the engine pistons merely through its elastic expansion and without explosive action. In the most complete embodiment of my invention, however, I propose to employ motive-fluid in the form of a combustible mixture, and to this end Fig. 2 illustrates a reservoir 28 containing gasolene, or other liquid fuel, and connected, through a pipe 29, with the 80 valve 26 so as to supply combustible vapor to the air introduced into the engine through the pipe 23, in a manner which will be hereinafter described.

The motive-fluid is compressed and forced 85 into the engine by an air-pump, and the power for actuating this pump is derived, as in my previous application above referred to, from an electric machine adapted to operate normally as a generator. As shown in 90 Fig. 2, the generator has an armature 30 and two field-windings 31 and 32. It normally supplies current to charge a storage-battery 33, and also for any other purpose, such as the operation of electric lights, ignition 95 apparatus, &c. upon the vehicle. In connection with the generator and the battery I employ a cut-out device 34 to prevent the return-flow of current from the battery through the generator when the latter 100 is at rest. As such devices are well known, I have not particularly described the construction thereof, but have merely illustrated the device in conventional form.

The diagram also illustrates an automatic 105 cut-out device for interrupting the charging operation when the battery is fully charged, this device being illustrated conventionally as comprising a contact-finger 35 co-operating with a fixed contact 36 and actuated by 110 a magnetic core 37 under the influence of a solenoid 38.

In the normal operation of the electric machine as a generator, when the engine is running, current flows from the armature, through wires 39 and 40 and through the main field-winding 31, to the contact-devices 36 and 35, and thence, through a wire 41, back to the armature. Current also flows from the wire 39 through the return-current 115 cut-out 34, and, through a wire 44, to the field-winding 32. This field-winding is wound in opposition to the main field-winding 31, so that it acts automatically, in a well-known manner, to limit the electro-motive force of the generator and prevent unduly rapid charging of the battery. From the opposition field-winding 32 the current flows, through a wire 45, to the battery, and returns thence through wires 46 and 41 to 120 125 130

the armature of the generator. A wire 47 is connected with the wire 44, and thus with one pole of the battery, and the wires 46 and 47 constitute main-conductors from which current may be drawn for any required purpose, as, for example, to energize an electric light 48.

The starting-apparatus is connected with manually-operable means for throwing it into operation from any convenient point on the vehicle. As shown in Fig. 2, the movable member of the valve 26 is provided with an arm 51 pivoted to a connecting-rod 52, of which the lower end is pivoted on a pin 53 projecting from a drum 54. A cable 55 passes around the drum 54, and thence, between guide-pulleys 56, to and around a second drum 57. An arm 58 is fixed to the drum 57, and, by swinging this arm, the drum may be turned through substantially half a rotation, thus turning the drum 54 in either direction through somewhat more than a half-rotation, as the drum 54 is of less diameter than the drum 57. In this manner the valve 26 may be actuated to throw the apparatus into operation. As it is necessary that the ignition-apparatus of the engine be in position for late or retarded ignition when the starting-apparatus operates, the manually-operable mechanism just described is preferably correlated with the controlling-means for the igniting-devices. As shown in Fig. 2, the lever 60, which is ordinarily used to control the time of ignition, is fixed to a shaft 59 concentric with the drum 57, and the arm 58 is provided with a lug 61 adapted to engage the lever 60. Accordingly, when the arm 58 is moved to the position shown in Fig. 2 to throw the starting-apparatus into operation, the lug 61 operates to move the lever 60 to a position to produce retarded ignition, unless the lever happens already to be in such position. As the lever 60 may be the ordinary "spark-lever", such as is commonly employed upon motor-vehicles, I have not illustrated its connections with the ignition-apparatus of the engine.

When the starting-apparatus is thrown into operation it is necessary to short-circuit the cut-out 34 to permit current to flow from the battery through the electric machine and cause the latter to operate as a motor. To this end the drum 54 is provided with an insulated contact-strip 62 adapted to coöperate with two fixed contacts 63 and 64. When the drum is rotated to the position of Fig. 2 the contact-strip electrically connects the fixed contacts, and current can then flow from the battery through the wire 45, the field-winding 32, and the wire 44 to the fixed contact 64, thence through the contact-strip 62 to the fixed contact 63, and thence, through the wire 39, to the generator, thus passing in a shunt or short-circuit

around the device 34. A third fixed contact 65 is provided, and upon the completion of the above-described movement of the drum 54 the contact-strip 62 is brought into engagement with this third contact, and in this manner a short-circuit is provided around the opposition field-winding 32 through wires 66 and 44. This arrangement constitutes no part of the present invention, but is disclosed, together with the advantage resulting therefrom, in my copending application filed October 9, 1911, Serial No. 653,670.

The details of construction of the principal portions of the starting-apparatus, in the preferred embodiment of the invention, are shown particularly in Figs. 3 to 9, inclusive. The base-plate 71, upon which the apparatus is mounted, is fixed, by means of screws 72, to the supports 12, which are in the form of angle-bars, as shown particularly in Figs. 6 and 7. The base-plate is provided with lugs 73 upon which the outer casing 11 of the apparatus is removably mounted, spring-pressed hooks 74 of well-known form being employed to secure this casing removably in place. The gearing by which the different portions of the apparatus are connected is inclosed within an inner oil-tight casing 75, of which the lowermost portion is formed integral with the base-plate 71.

Midway of the base-plate a short shaft 76 is journaled in bearings fixed in the casing 75, and this shaft is so positioned that it is substantially in alinement with the crank-shaft of the engine. By means of a coupling 77 of the well-known Oldham type the shaft 76 is connected with the engine-shaft so as to rotate always with the latter. A spiral gear 78 is fixed to the shaft 76, and it meshes with a spiral pinion 79 which is keyed to a hollow shaft 80, hereinafter referred to as the "countershaft." This countershaft extends transversely with respect to the shaft 76 and the engine-shaft, and constitutes a connection between these latter shafts and the air-pump and the electric generator, which are located upon opposite sides of the shaft 76, thus securing a compact and symmetrical arrangement of parts with respect to the center of the vehicle.

The countershaft 80 is journaled upon a solid concentric shaft 81, which, in turn, is mounted in ball-bearings 82 and 83 in the casing 75. The right-hand end of the shaft 81 is connected, by a coupling 85, with the armature-shaft of the electric generator 84. The left-hand end of the counter-shaft is provided with an integral shell 86 constituting one member of a one-direction clutch, of which the other member is formed by an enlargement 87 on the shaft 81. These clutch-members are connected by spring-pressed friction-rollers 88 arranged, in a well-known manner, to cause the member 86, 130

when rotating in the direction of the arrow applied thereto in Fig. 7, to rotate the member 87. Accordingly, during the normal operation of the engine, power is transmitted from the engine through the shaft 76, the gears 78 and 79, to the countershaft 80, and thence, through the clutch just described and the shaft 81, to the electric machine, causing the latter to operate as a generator.

The air-pump is illustrated as having two cylinders 91, inclosing pistons 92 which are connected with an eccentric-strap 93 actuated by an eccentric 94. This eccentric is integral with a hollow shaft 95 which is journaled upon a concentric rock-shaft 96. The shaft 95 is provided also with an integral gear 97 which is adapted to coöperate with a pinion 98 fixed to the shaft 81. The gear and the pinion are not normally in engagement, but may be thrown into engagement, when the starting-apparatus is to operate, through a partial rotation of the rock-shaft 96. This rock-shaft has eccentric extremities 99 and 100 journaled in the casing 75, and by suitable connections with the drum 54 the rock-shaft may be turned so that the eccentric movement of its larger portion raises the hollow shaft 95, and thus causes the gear 97 to engage the pinion 98. Upon such engagement power derived from the electric machine, acting as a motor, through the shaft 81, may be employed to actuate the air-pump.

Since the gear-teeth may not always be in a position to engage each other immediately when the rock-shaft is turned, provision is made for lost motion in the mechanism until such engagement occurs. To this end the drum 54 is not rigidly connected with the extremity 100 of the rock-shaft, but is loosely journaled thereon, being fixed to a concentric sleeve 106 provided, at its inner end, with an arm 107. This arm moves within a casing 101 which incloses a spiral spring 108. One end of this spring is fixed to the arm 107, and the other end is fixed to the rock-shaft, as shown particularly in Fig. 8. Accordingly, when the drum 54 is rotated it tends to increase the torsion of the spring, and thus to rotate the rock-shaft. Movement in the opposite direction is rendered positive through the coöperation of a pin 103, fixed to the drum 54, and a lug 102 fixed to the extremity 100 of the rock-shaft. A second lug 104 is fixed to the rock-shaft within the casing 101, and this lug coöperates with stop-lugs 105 upon the casing 75 to prevent the shaft from rotating too far in either direction.

The inlet-ports of the air-pump cylinders are not provided with valves, but are arranged to be covered and uncovered by the pistons, being in the form of elongated openings 111 located in the sides of the cylinders,

as shown in Fig. 5. These ports communicate with passages 112 which terminate just above a shallow receptacle 113. When the pump is used to force combustible mixture into the engine, gasoline is discharged into the receptacle 113, and the air is drawn over this gasoline through the restricted ends of the passages 112, thus vaporizing the gasoline. The arrangement of the inlet-ports just described not only simplifies the construction of the air-pump, but it also facilitates the vaporization of the gasoline, since it causes the air to enter the pump-cylinders suddenly, as a result of the vacuum produced by the descent of the pistons before the ports are uncovered, and the resulting rush of air over the gasoline is so violent as to pick it up and reduce it at once to a fine spray or vapor. The outlet-ports of the air-pump cylinders are controlled by spring-pressed check-valves 114, and the compressed motive-fluid is forced through pipes 115 connected with the casing 116 of the air-valve 26.

The valve is in the form of a conical plug, 90 provided with a stem 118 to which the arm 51 is fixed. This valve-member has inlet-openings 122 communicating, in all positions, with the pipes 115 so as to admit the compressed air from the pump, and from these inlet-openings the air passes, through an axial opening, to a radial outlet-port 123. According to the position of the valve 26 this outlet-port may register either with the pipe 23 before referred to, to direct the compressed air to the distributor, or with a pipe 124. This latter pipe constitutes an outlet which may normally discharge into atmosphere, but which may also be employed to discharge compressed air from the pump 105 into suitable connections for conducting it to the tires of the motor-vehicle, thus permitting the air-pump to be used as a tire-inflating device as well as for starting the engine.

In Fig. 5 the valve 26 and its actuating-mechanism are shown in three positions. The full lines show the parts in their normal position, in which the pump-actuating gearing is inoperative. Under these conditions the air-pump is motionless. By a partial rotation of the drum 54, through somewhat less than 180 degrees, the parts are moved to the position shown in dotted lines 125. Here the positions of the connecting-rod 52 and the pin 53 are changed, but the relation of the parts is such that the arm 51 and the valve 26, although having been moved during the rotation of the drum, have returned again to their normal position, so that the outlet-port 123 still registers with the pipe 124. Accordingly, the pump may now be actuated by power from the engine, and the air so compressed is discharged through the pipe 124. This is the position 130

to which the parts are moved when it is desired to supply compressed air for inflating the tires, or for any other purpose, by actuating the air-pump by power derived from the engine while the latter is running.

5 When the apparatus is to be used to start the engine the drum 54 is moved to the limit, that is, so that the parts assume the position shown in dotted lines 126 in Fig. 5. In 10 this position the arm 51 and the valve 26 are rocked to the left of the position of Figs. 4 and 5, so that the outlet-port 123 registers with the pipe 23 and admits the air through the distributor and into the engine. At this 15 time the gasoline is also discharged into the receptacle 113. For this purpose the valve-member 26 is provided with a transverse passage 129 which is adapted to register, in the position of the valve last described, with 20 a gasoline passage 128 in the valve-easing, supplied through the pipe 29, as shown in Fig. 3. The flow of gasoline is controlled by an adjustable needle-valve 127 by which it may be regulated to produce a combustible 25 mixture.

25 The valve-member 26 is held firmly against its seat by means of a coiled spring 130, which is inclosed within a cap 131 engaging a pin 120 fixed in the valve-stem 118. 30 The details of construction of the electric circuit-controller actuated by the drum 54 are shown particularly in Figs. 8 and 9. Each of the fixed contact-members 63, 64 and 65 is in the form of a spring-pressed 35 plunger mounted in a binding-post 132, and the binding-posts are fixed to, but insulated from, the casing 101. On the inner surface of the drum 54, at its periphery, is a plate of insulating material 133 upon which is 40 mounted the contact-strip 62, in position to engage the ends of the contact-devices when the drum is rotated to throw the starting-apparatus into operation. The contacts 64 and 65 are so located that they are not engaged by the contact-strip 62 when the drum is moved to the position 125 in Fig. 5, as in 45 this position the power of the engine is used to actuate the air-pump, and the electric machine operates still as a generator. The 50 further or final movement of the drum, however, brings the contact-strip successively into engagement with the contacts 64 and 65 as above described.

55 In addition to forcing motive-fluid into the engine-cylinders the apparatus is arranged to impart power directly to the engine-shaft for the purpose of rotating the engine, as described in my pending application filed October 9, 1911, Serial No. 653, 60 671. To this end the hollow shaft 95 is provided with an integral pinion 135, which is adapted to mesh with a gear 136 when the rock-shaft 96 is turned to throw the gearing into operative position. The gear 136 is 65 provided with a hardened steel ring 137,

which constitutes a clutch-member adapted to coöperate with the shell 86 on the counter-shaft 80. Spring-pressed friction-rollers 138, interposed between these parts, are arranged to cause the gear 136 to rotate the 70 shell 86 and the countershaft, and thus to rotate the crank-shaft of the engine when the engine is not in operation. Accordingly, when the air-pump is thrown into operation by power derived from the electric machine, 75 a portion of this power, acting through the reduction-gearing comprising the pinion 98, the gear 97, the pinion 135 and the gear 136, acts to rotate the engine slowly and thus to assist the starting-operation. As soon as 80 the engine starts to operate by its own power, however, the one-direction clutch-mechanism comprising the ring 137, the shell 86 and the friction-rollers 138, permits the countershaft to be rotated by the 85 engine at a speed greater than that with which the gear 136 is moving.

90 In the normal operation of the engine the gear 136, being disengaged from the pinion 135, rotates idly at the same speed as the shell 86, so that there is no friction between these parts, and accordingly it is unnecessary to provide any journal for the gear 136 other than that provided by the clutch-mechanism itself. A thrust-bearing 140, 95 however, is interposed between the gear 136 and the casing to sustain the thrust upon the countershaft produced by the spiral gears 138 and 139, in one direction, and the opposite thrust is taken up by a thrust-bearing 142 interposed between the pinion 79, and the casing. An annular bearing 141 is also interposed between the countershaft and the casing.

100 As occasions may arise when it is convenient to employ manual power in starting or moving the engine, the forward end of the shaft 76 is provided with a toothed clutch-member 143 adapted to coöperate with a manually-operable starting-crank of 105 ordinary form, and to admit this crank the outer casing 11 is provided with an opening covered by a swinging door 144, as shown in Fig. 1.

110 Referring to Fig. 1, it will be apparent that the relative arrangement of parts of the mechanism hereinbefore described produces a compact and substantially symmetrical structure capable of being mounted in the position described without undue projection in any direction, and with the weight of the parts symmetrically distributed. The pump-mechanism on one side of the central shaft 76 balances the generator 84 on the other side, and this arrangement is permitted by the use of the countershaft connected with the engine-shaft by spiral gearing, as hereinbefore described. In applying the starting-apparatus to an automobile, the angle-bars 12 are fixed to the side frame- 115 120 125 130

members, which may be conveniently done as these frame-members are usually at a certain standard distance apart in automobiles of various makes as now constructed. The coupling 77, which is of the Oldham type, is adapted to accommodate itself to any slight inaccuracies in lining up the shaft 76 with the engine shaft, and the flexible cables 55 are adapted to be led in any required direction, and to any required distance, to a convenient point for the location of the drum 57. The only part of the mechanism which is located within the hood which covers the engine is the selector, and this takes up very little room and usually may be mounted upon the same shaft as is employed to actuate the electric ignition-apparatus of the engine.

The starting-apparatus hereinbefore described is adapted, without changes in its construction, to operate in various ways. It may be employed either to force combustible mixture into the engine-cylinders, or to start the engine by simply compressing air, utilizing the elastic expansion of the air without ignition. The use of the gearing for rotating the engine shaft is also optional. By the removal of the gear 136 this function of the apparatus may be omitted, thus relieving the electric machine of a part of the work otherwise required of it, and this may be done, for example, in the case of a six-cylinder engine, which has no position of dead-center and in which at least one of the pistons is always in a position favorable for the starting-operation.

My invention is not limited to the embodiment thereof hereinbefore described and illustrated in the accompanying drawings, but may be embodied in various other forms within the nature of the invention as it is defined in the succeeding claims.

I claim:—

1. Engine-starting apparatus for automobiles having, in combination, a transverse support adapted to be carried, as its ends, upon the side frame-members of an automobile in front of the engine thereof, a rotary member journaled at the middle of said support, in position to align with the engine-shaft, means for coupling the engine-shaft and said member, a countershaft, journaled on said support, transverse to said rotary member and rotatively connected therewith, and an air-pump and an electric machine located on opposite sides of the rotary member and operatively connected therewith through the countershaft.

2. Engine-starting apparatus having, in combination, a motor, a pump for supplying motive-fluid to the engine to be started, gearing adapted to connect the motor with the engine and the pump to actuate them simultaneously, and a one-direction clutch interposed in said gearing and adapted to

permit the engine to overrun the motor and the pump after the engine has started to operate.

3. Engine-starting apparatus having, in combination, a motor, a pump for supplying motive-fluid to the engine to be started, reduction-gearing adapted to connect the motor with the engine and the pump to actuate them simultaneously, manually-operable means for throwing said gearing into or out of operation, and a one-direction clutch interposed between the engine and the gearing to permit the engine to overrun the gearing after the engine has started to operate.

4. Engine-starting apparatus having, in combination, a motor, an air-pump for supplying motive-fluid to the engine to be started, a fuel-valve for controlling the introduction of fuel to the air supplied by said pump to the engine, gearing for connecting the motor with the pump, and manually-operable means for simultaneously throwing said gearing into operation and opening said valve.

5. Engine-starting apparatus having, in combination, a motor, an air-pump for supplying motive-fluid to the engine to be started, means for introducing fuel into the air supplied to the engine by said pump, gearing for connecting the motor with the pump and the engine to actuate them simultaneously, and manually-operable means for throwing the motor, the gearing, and the fuel-introducing means simultaneously into operation.

6. Engine-starting apparatus having, in combination, a motor, an air-pump for supplying motive-fluid to the engine to be started, means for introducing fuel into the air supplied to the engine by said pump, gearing for connecting the engine, the pump, and the motor, and manually-operable controlling-means operable either to throw the gearing into operation to permit the engine to actuate the pump, or to throw the gearing, the fuel-supplying means and the motor into operation to force combustible mixture into the engine to start the latter.

7. Engine-starting apparatus having, in combination, a motor, a motor-shaft connected therewith, a countershaft concentric with the motor-shaft and adapted to be connected with the crank-shaft of the engine to be started, a gear concentric with the countershaft and the motor-shaft, reduction-gearing for connecting the motor-shaft with said gear, a pump connected with the reduction-gearing so as to be operated thereby, means for throwing the reduction-gearing into or out of operation, and one-direction clutches for connecting the countershaft with the motor-shaft and the gear, respectively.

8. Engine-starting apparatus having, in combination, a fuel-receptacle, means for supplying liquid fuel thereto, an air-pump for drawing air through the fuel-receptacle and forcing the air into the engine to be started, and means for actuating the pump; the pump having a piston, and a cylinder provided with an inlet-port connected with the fuel-receptacle and located in position to be controlled by the piston and to be uncovered only near the end of the out-stroke of the piston. 10

EDWARD A. HALBLEIB.

Witnesses:

FARNUM F. DORSEY,
D. GURNEE.

Copies of this patent may be obtained for five cents each, by addressing the "Commissioner of Patents, Washington, D. C."

Correction in Letters Patent No. 1,072,002.

It is hereby certified that in Letters Patent No. 1,072,002, granted September 2, 1913, upon the application of Edward A. Halbleib, of Rochester, New York, for an improvement in "Engine-Starting Apparatus," an error appears in the printed specification requiring correction as follows: Page 6, line 46, for the word "as" read *at*; and that the said Letters Patent should be read with this correction therein that the same may conform to the record of the case in the Patent Office.

Signed and sealed this 30th day of September, A. D., 1913.

[SEAL.]

R. T. FRAZIER,
Acting Commissioner of Patents.

Correction in Letters Patent No. 1,072,002.

It is hereby certified that in Letters Patent No. 1,072,002, granted September 2, 1918, upon the application of Edward A. Halbleib, of Rochester, New York, for an improvement in "Engine-Starting Apparatus," an error appears in the printed specification requiring correction as follows: Page 6, line 46, for the word "as" read *at*; and that the said Letters Patent should be read with this correction therein that the same may conform to the record of the case in the Patent Office.

Signed and sealed this 30th day of September, A. D., 1913.
